UNITED STATES PATENT OFFICE

FRANK BOWERS, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed November 6, 1922. Serial No. 599,355.

This invention relates to boiler cleaners and refers more particularly to boiler cleaners of the type in which a rotating blower pipe or unit is employed for discharging jets 5 of steam or other cleaning fluid against the tubes or other surfaces to be cleaned.

One of the main objects of the invention is to provide an improved automatic valve arrangement whereby the supply of steam to the blower unit is automatically controlled so as to be opened at predetermined portions 10 only of the rotation of the unit; to provide a valve arrangement which is accessible so that it can be readily removed and the valve port 15 increased to meet the desired amount of rotation required; to provide a construction which will permit of a rotation of the unit through a substantially complete arc while the valve is in the open position; to provide 20 a valve which will be automatically held to its seat in a closed position, preferably by the pressure of the steam; and in general to provide a new and improved construction of the character above referred to.

25 In the drawings:

Fig. 1 is a vertical sectional view partly in elevation showing one embodiment of my invention.

Fig. 2 is a section through the line 2—2 of

30 Fig. 1.

Describing the construction shown in Figs. 1 and 2, A designates the blower pipe having nozzles A' adapted to discharge jets of steam against the tubes A². Steam to the blower 35 pipe A is provided by an inlet pipe B, the communication between which and the blower pipe is controlled by a valve mechanism as follows: At its outer end the blower pipe A is provided with the enlarged extension C having the port C'. This extension is mounted 40 within the blower head or housing D which is sufficiently greater in diameter than the extension C as to leave a space D' through which steam from the inlet B can pass around the extension C. Surrounding the extension C there is provided a member E secured 45 against rotation by the set screw R, the member E being cut away at E' as shown in Fig. 2 so as to leave a port of whatever size desired, 50 which port when in registration with the

port C' will permit steam to pass from the inlet pipe B to the blower pipe A. When, however, the port C' is rotated so as to come in contact with the portion of the member E which is not cut away, communication between the inlet pipe B and the blower pipe A will be cut off. It is to be noticed that in this cut off position the steam will be on the outside of the member E and the steam pressure of the boiler will therefore tend to contract the member E about the extension C and form a tight seal to prevent leakage. For rotating the blower pipe there is provided a chain wheel F about which a chain F' extends, this chain reaching to the floor or other 60 convenient position for use. The chain wheel F is fixedly secured to the end G of the blower pipe so that upon rotation of the blower pipe the ports E' and C' will come into registration and remain in registration during predetermined portions of the rotation of the blower pipe. In the particular construction shown in the drawings, these ports are so proportioned that steam is supplied to the blower pipe while the latter is rotating 65 through 180°. As before pointed out, the port in member E may be varied to provide a steam supply to the blower pipe through any desired arc of rotation.

One important feature of the invention is 70 the fact that by removing the casing D the member E can be readily removed. Thus to change the installation to take care of different arcs of rotation through which the steam should be discharged so as not to discharge 75 against the baffles, it is only necessary to remove the member E and either substitute another member or else to cut a larger opening E' in the member E.

By making the extension C, provided with 80 port C', of greater diameter than the blower pipe A, I provide a construction which will avoid restriction of the steam where it enters the blower pipe. In a cylindrical valve, in order to make it quick opening, the port is made narrow and long. With such construction 85 the diameter of the valve is ordinarily made substantially the same as that of the blower pipe, restriction of the steam then occurring 90 immediately beyond the point where the 95

100

valve port ends. With my construction this objectionable restriction of the steam is prevented.

What I claim as my invention is:

- 5 1. In a boiler cleaner, a blower head, a cleaning fluid supply pipe, a blower pipe provided with an enlarged portion located within said blower head, the enlarged portion having an inlet port, a member mounted in said head but circumferentially spaced therefrom, said member being fixed against movement with said blower pipe and being adapted to periodically cover and uncover said port, and means for moving the blower pipe relative to said member.
- 10 2. In a boiler cleaner, a rotatable blower pipe provided with nozzles for the discharge of steam adjacent the heating surfaces of the boiler, a cleaning fluid supply pipe therefor, a fitting mounted exteriorly of the boiler and forming a connection between said blower pipe and said cleaning fluid supply pipe, said blower pipe being provided with an enlarged portion journaled in said fitting, the enlarged portion having an enlarged inlet port, a member fixed against movement with said blower pipe mounted in said fitting and circumferentially spaced therefrom for periodically covering and uncovering said port, said member so cooperating with said enlarged portion of the blower pipe as to be subjected to steam pressure tending to maintain the member in sealing contact with the enlarged portion of the blower pipe.
- 15 3. In testimony whereof I affix my signature.

FRANK BOWERS.
